UNITED STATES PATENT OFFICE

PLINY P. PIPES, OF MANSFIELD, OHIO, ASSIGNOR TO THE OHIO BRASS COMPANY, OF MANSFIELD, OHIO, A CORPORATION OF NEW JERSEY

RAIL BOND

Application filed November 9, 1927. Serial No. 232,062.

My invention relates to rail bonds for electrically connecting the adjacent ends of rails.

The object of my invention is to provide a bond which is adaptable for applying by means of an oxy-acetylene flame or other gaseous flame and the flame of the electric arc, and applied by means of either a steel electrode, copper electrode or copper having 50 associated therewith a reducing agent.

My invention resides in the new and novel construction, combination and relation of the parts hereinafter described and shown in the accompanying drawings.

In the drawings:

Fig. 1 is a top view of the bond as positioned against a side surface of adjacent rail ends but not welded thereto.

Fig. 2 shows a side view of the bond.

Fig. 3 shows an end view of the bond as positioned against the side face of a rail, as in Fig. 1.

Figs. 4 and 5 are sectional views taken on the lines 4—4 and 5—5 respectively of Fig. 2.

Fig. 6 is a sectional view on the line 6—6 of Fig. 1, showing the bond terminal as welded to the side face of the rail by means of a copper flux attaching metal.

Fig. 7 shows a sectional view of the terminal on the line 7—7 as positioned against the rail in an inverted position from that in Figs. 3 and 6 and welded to the side surface of the rail by means of steel attaching metal.

There are times when it is desirable to have 35 a bond which can be secured to the side surface of a rail by either steel or copper and by means of either the oxy-acetylene flame or the electric arc, and I have provided a bond adapted for such varied application, and the same comprises the flexible body member 1 and terminal 2 secured together and having an interposed sleeve 3.

I prefer to make the body member of copper and the terminal member of steel or iron, although it may be made of copper or

other suitable metals. If made of steel, then I am able to carry out all the objects named above, and especially uniting the terminal to the rail by means of steel or iron attaching metal, which cannot be done if the terminal is composed of copper. The terminal member 2 comprises an elongated trough-like portion 4, closed at one end, and its opposite end projecting from a sleeve portion 5 adapted to receive and grip the body 1. The terminal 2 is preferably formed up out of sheet metal of uniform thickness, and this can be readily done by means of proper dies or stamping and forming the sheet metal. When made in this manner, there will be a 55 split or seam 6 in the sleeve portion 5. The terminal 2 can be made of a casting such as malleableized cast iron, brass, bronze or copper, or it may be formed up as a forging and the sleeve portion 5 drilled to receive the body member 1 and sleeve 3.

The portion 4 has a straight longitudinally disposed side 7 adapted to be applied to the rail surface. Also, the side 7 is preferably made with a flat surface of limited vertical height, although this is not entirely necessary. The opposite edge 8 of the terminal is formed to extend above the edge 7 when the bond is positioned on a rail, as indicated by the space 8 between the dotted lines in 60 Fig. 4. This forms a comparatively large receptacle to receive the molten attaching metal, which, in this case, is copper, bronze or copper associated with a reducing agent.

The end of the body member projects beyond the sleeve portion 5 and into the trough-like receptacle 9, and this permits the attaching metal 10 to be fused to the inner surface of the receptacle 9 and the upper edges of the terminal portion 4 and also to the end face 65 11 of the body member 1, thereby uniting the terminal, body member 1 and the rail together through the medium of the welding metal 10.

The receptacle 9 receives the copper base welding metal 10, but is not adapted to re- 70 75 80 85 90

ceive a ferrous welding metal, for the reason that the molten steel or iron would not unite properly with the end face 11 of the body 1, but when it is desired to apply the bond to the 5 rail by means of the oxy-acetylene or other gaseous flame, or electric arc, using a copper base attaching metal, such flame and metal are applied to the receptacle 9, the end face 11, to the side face of the rail and also to the 10 edges 14 of the terminal.

If it is desired to use steel or iron attaching metal, the operator will first apply a copper base metal to the receptacle 9 and the end face 11 and the body 1, although this is preferably done by the manufacturer at the time 15 of manufacture of the bond, so as to fill up the receptacle and unite the end face 11 to the terminal 2. This electrically unites the body member 1 and the terminal member 2 20 in a very efficient and secure manner. Having done this, the operator then applies the bond to the rail in the reverse position from that shown in Fig. 1, that is, the receptacle side would then be positioned downwardly.

25 In Fig. 7 is shown a section of a terminal taken on the line 7—7 as applied to the side surface of a rail by means of steel or iron attaching metal 12. The terminal portion 4 shown in the opposite position from that in 30 Fig. 1, and the copper base attaching metal, referred to above, and positioned in the receptacle 9, is indicated by the numeral 13.

Having positioned the bond against the rail surface, the attaching metal 12 of steel 35 or iron is applied by means of the oxy-acetylene flame or the electric arc. This units the terminal directly to the rail through the medium of the welding metal 12 and the bond is attached to the terminal by means of the 40 attaching metal.

The sleeve 3 is usually made of copper and quite thin, and prevents the edges of the sleeve portion 5 from cutting into the strands of the copper member 1, and the sleeve 3 tends to 45 dampen vibration, prevents crystallization of the strands adjacent the outer edge of the sleeve 5.

The sleeve portion 5 is arranged to mechanically grip the end of the body member 50 1 in a very secure manner to hold the body and terminal together such that it is not necessary to depend upon the welded joint between the body 1 and the metal 10 or 13 to 55 secure these parts together.

The face 11 of the body member is preferably cut on an angle so that the face is angularly disposed upwardly in order that the heating flame can be directly applied to 60 the face 11, which will assure the operator that all portions of the end face 11 are united to the attaching metal 10 or 13, as the case may be. If the face 11 is at right angles to the axis of the adjacent portion of the body, 65 the operator is not assured that the entire

face 11 will be properly joined to the welding metal 10 or 13.

By tapering the terminal portion 4, as indicated at *a*, Fig. 2, a better application of the heating flame is permitted, especially in 70 the case of the electric arc and also increases possible contact area of the welding metal with the rail for a given length of bond terminal, without sacrificing any features necessary to the efficiency of the bond.

75 By having the edge 7 of the terminal portion 4 positioned lower than the edge 8, I am able to secure a larger area of contact between the welding metal 10 and the rail surface, as shown in Fig. 6.

80 In using the electric arc in welding, I may use either a steel or copper base electrode, or I may use a carbon electrode and a filling rod of steel or iron, or a copper base metal, which is melted down by the arc flame of the carbon electrode.

85 It will be seen that my bond is quite universal in its application, and that it can be applied by any of the various heating flames now common in the art and by means of a copper base or ferrous base welding metal.

90 This bond also has the advantage that after it has been installed in one of the two positions referred to, it can be pried off the rail and applied in the other position if desired at another point on the electric system.

95 It will be noted that the side 7 and bottom of the terminal are substantially at right angles and that when the bond is applied to the rail, as in Fig. 7, the bottom of the terminal 100 forms a shelf projecting from the rail at substantially right angles thereto.

There will be modifications evident to those skilled in the art, but I wish to be limited only by my claims.

105 I claim:

1. A terminal adapted to be welded to a rail in either of two positions comprising a portion to receive and grip a cable, the axis of the cable being extended longitudinally of the rail in either of said positions, a projecting portion having bent-up edges at all sides thereof except that at which the cable is gripped from the first portion and forming an open top receptacle for molten metal either before the terminal is applied to the rail or during its application to the rail, the said receptacle arranged to catch and support molten attaching metal when the terminal is applied to the rail in one of said positions and the projecting portion forming a shelf upon which the attaching metal can be applied when the terminal is applied to the rail in the other of said positions.

110 2. A rail bond terminal adapted to be applied to a rail in either of two positions, said terminal comprising a portion to receive and grip a body member, a projecting portion from the end face of the receiving portion and forming a receptacle, the projecting por-

tion having a substantially flat bottom and also a substantially flat side to be positioned along the rail and a curved side having its edge portion substantially parallel with the edge of said flat side, the receptacle adapted to catch and retain molten metal when the terminal is applied to the rail in one of said positions and to form a substantially flat shelf projecting from the rail to catch and support molten metal when applied in the other of said positions.

In testimony whereof I affix my signature.
